THROTTLE VALVE CONTROL MECHANISM
FOR INTERNAL-COMBUSTION ENGINES

Alexander Arnold Issigonis, Cowley, Oxford, England, assignor to Morris Motors Limited, Cowley, Oxford, England

Application September 27, 1943, Serial No. 504,014
In Great Britain October 20, 1942

2 Claims. (Cl. 251—152)

This invention relates to the throttle valve control mechanisms used for controlling the supply of combustible mixture to the cylinders of vehicle and other internal combustion engines.

It is a common practice to provide such a mechanism with an adjustable stop for determining the extent to which the valve can be moved towards its closed position, this stop being usually so adjusted as to prevent complete closing of the valve and to allow (when the engine is idling) sufficient flow past the valve to keep the engine in motion. On some engines and more particularly two-stroke engines when the valve is allowed to move quickly from the fully open position to the nearly closed position determined by the stop, there results a considerable depression of pressure in the induction system leading to the engine, with a consequent risk of the combustible mixture in the said system becoming ignited. This condition is undesirable and may sometimes be dangerous. The object of the present invention is to provide an improved throttle valve controlling mechanism whereby the said risk is obviated.

The accompanying drawing illustrates one mode of carrying the invention into effect.

In the drawing, the general outline of a carburettor is indicated by the letter *a*, the air inlet being at *b* and the mixture outlet at *c*. The outlet is adapted to be connected to the induction system of the engine. The carburettor shown in the drawing is of the down draught type. In the outlet is pivoted the throttle valve *d*, this being of the usual butterfly type. To the spindle *e* of the valve is secured a bell crank lever *f*, the long arm of which is connected by a link *g* to a pedal *h*, the latter being actuated in the direction for closing the valve by a spring *i*. The short arm of the lever is provided with an adjustable screw *j* which can abut the stop *k*.

According to the form of my invention illustrated by the drawing the stop *k* is slidably supported in a casing *l* which also carries a plunger *m* slideable in a direction at right angles to the stop, and the lower end of the plunger *m* is tapered as shown. The upper end of the plunger *m* is attached to a diaphragm *n* contained in a chamber *o* formed by the casing, the diaphragm being gripped in a gas tight manner around its peripheral portion between two parts of the casing. The upper part of the casing contains a spring *p* which tends to urge the diaphragm and plunger in the downward direction, and this end of the casing is connected by a pipe *q* to a point on the outlet *c* at the engine side of valve *d*.

Normally the diaphragm occupies a central position in the chamber *o* and when the diaphragm is in this position the plunger occupies a position in which its cylindrical surface is in contact with the adjacent end of the stop. This condition determines the partially closed position of the valve *d* as indicated by the dotted lines in the drawing, this being the position occupied by the valve during normal slow running or idling of the engine. Adjustment of this position of the valve can be effected by the screw *j*. The plunger is held in the said lower position by the spring *p* which is sufficiently strong to overcome the upward thrust caused by the pressure of the stop on the tapered portion of the plunger.

When a sufficient depression of pressure occurs in the induction system the atmospheric pressure acting on the underside of the diaphragm moves the latter upwards against the action of the spring *p* into the position shown, thereby raising the plunger and bringing the tapered surface of the plunger behind the stop. The stop can now move to the position in which it allows the valve to be fully closed as represented by the full lines in the drawing.

When the engine is running under normal speed and load conditions the diaphragm occupies its central position and the tapered portion of the plunger lies below the stop. Consequently the latter is held in the position corresponding to partial closing of the valve. So long as the pressure in the induction system continues to be insufficient to affect the diaphragm, the stop remains in the position mentioned. But if the throttle is allowed to close rapidly and if in consequence a sufficient depression of pressure is set up in the induction system, the plunger is raised to the upper position shown by the drawing, allowing the stop to take up its other position and permit the throttle valve to become fully closed. Complete closure of the throttle valve prevents continued entry of mixture to the engine with the result that the engine speed falls rapidly and the pressure in the induction system consequently rises. Thereupon the diaphragm and plunger return to the normal position causing the stop to be pushed to the other of its two positions and the valve to open sufficiently to maintain the engine in motion.

By interrupting the supply of mixture to the engine temporarily when the throttle valve is allowed to close rapidly the condition which otherwise tends to result in a risk of ignition of the charge in the induction system is obviated.

As already stated the invention is more especially useful on two-stroke engines but it may be applied if desired to other internal combustion engines, as used on vehicles or for other like purposes.

The invention is not, however, restricted to the example described as subordinate constructional details may be varied to suit different requirements. Thus the diaphragm may be replaced by a piston slideable in a cylindrical chamber, and instead of a slideable stop an angularly movable stop may be used.

Having thus described my invention what I claim as new and desire to secure by Letters Patent is:

1. A throttle valve control mechanism for internal combustion engines, comprising a movable stop for determining the extent of the closing

movement of the throttle valve, a relatively movable abutment by which the stop is constantly supported, and means responsive to the pressure in the portion of the induction system between

5 the valve and engine for varying the position of the abutment, the latter being shaped and arranged so that it is movable by the said means between a normal position in which the stop can serve to prevent complete closure of the valve, and another position in which the stop permits complete closure of the valve.

10 2. A throttle valve control mechanism as claimed in claim 1, in which the abutment consists of a slideable plunger having a tapered portion which permits movement of the stop into the position for permitting complete closure of the valve.

ALEXANDER ARNOLD ISSIGONIS.
